United States Patent

Des. 236,704
Patented Sept. 9, 1975

236,704

TRUCK BODY

Fred T. Smith, Dearborn Heights, Mich., assignor to
Sargent Industries, Inc., Los Angeles, Calif.

Filed Dec. 28, 1973, Ser. No. 429,095

Term of patent 14 years

Int. Cl. D12—08

U.S. Cl. D12—15

FIG. 1

FIG. 2

Fig. 3

FIG. 4

FIG. 5

FIG. 1 is a left front perspective view of a truck body showing my new design;

FIG. 2 is a side elevational view thereof opposite to the side shown in FIG. 1;

FIG. 3 is a left rear perspective view thereof;

FIG. 4 is a top plan view thereof; and

FIG. 5 is a front elevational view thereof.

The broken lines in the drawings are for illustration purposes only.

I claim:

The ornamental design for a truck body, substantially as shown and described.
